United States Patent Office.

EBEN HESTER, OF SUFFIELD, CONNECTICUT.

Letters Patent No. 80,734, dated August 4, 1868.

IMPROVEMENT IN BELT-PUNCHES.

The Schedule referred to in these Letters Patent and making part of the same.

TO ALL WHOM IT MAY CONCERN:

Be it known that I, EBEN HESTER, of Suffield, in the county of Hartford, and State of Connecticut, have invented a new and useful Improvement in Belt-Tools; and I do hereby declare that the following is a full, clear, and exact description thereof, which will enable others skilled in the art to make and use the same, reference being had to the accompanying drawings, forming part of this specification, in which—

Figure 1 is a side view of my invention.

Figure 2 is a cross-section of the same, through the line x x of fig. 1.

Similar letters of reference indicate like parts.

The object of this invention is to furnish a convenient tool for fitting belts for machinery.

It consists of a square shank, B, set in a handle, A, and bearing two punches, b and d, for cutting holes in the belt, and two punches, e and f, having hollow or concave points for heading rivets.

It is also provided with a flat lacing-awl, a, having an eye, g, for carrying the leather lacing-strip.

The awl and the punches are detachable, if desired, but the tool is intended to be used as it is shown, the shank being turned to present the proper punch required, the flat head of which is struck upon by a hammer.

Having thus described my invention, I claim as new, and desire to secure by Letters Patent—

A belt-tool, constructed substantially as and for the purposes described.

EBEN HESTER.
